UNITED STATES PATENT OFFICE.

E McIVOR LAW, OF ARCADIA, FLORIDA.

CONVERTIBLE PROTECTIVE COVERING.

1,346,320.

Specification of Letters Patent. Patented July 13, 1920.

Application filed November 24, 1917. Serial No. 203,823.

To all whom it may concern:

Be it known that I, E McIVOR LAW, a citizen of the United States, residing at Arcadia, in the county of De Soto and State 5 of Florida, have invented certain new and useful Improvements in Convertible Protective Coverings, of which the following is a specification.

This invention has as its object to provide an article which may be employed to take the place of various outer garments and which also may be put to various other uses particularly adapting it for army use, and for use by farmers, fishermen, auto- 10 mobilists, etc., as well as by the general public. One of the aims of the invention is to provide an article of this class which may be manufactured at a low cost and which may be employed, for example, as an 15 overcoat, raincoat, cape, slicker, sleeping bag or tent or cover, wagon cover, automobile cover or soldier's pack cover as well as being adapted for use for various other purposes too numerous to mention.

20 The invention aims further to so construct the article that the same may be readily and quickly adapted to serve its various uses.

In the accompanying drawings:

25 Fig. 1 is a plan view of the article spread open and viewing the inner side or obverse face thereof;

Fig. 2 is a similar view looking at the outer side or reverse face;

30 Fig. 3 is a view illustrating the article employed as a rain or overcoat with an ordinary collar;

Fig. 4 is a similar view illustrating the article employed as an overcoat or raincoat 35 with a hood;

Fig. 5 is a similar view illustrating the manner in which the article is to be applied and adjusted for either of the uses shown in Figs. 3 and 4;

40 Fig. 6 is a perspective view illustrating the article partly folded to form a sleeping bag;

Fig. 7 is a similar view of the completely 45 folded article when employed in this manner.

Fig. 8 is a vertical longitudinal sectional view through the article, the view being taken substantially on the line 8-8 of Fig. 1;

50 Fig. 9 is a view illustrating the article employed as a shelter tent;

The article embodying the present invention is preferably formed from a single sheet of canvas, khaki cloth, or any other suitable fabric depending upon the general 60 use or uses to which it is contemplated that the article shall be put. This sheet of material is indicated in the drawings by the numeral 1 and the edge portions thereof at all four sides are folded in and stitched to 65 form hems, the hem along what will be the upper end of the article being indicated by the numeral 2, the one along the lower end by the numeral 3, one of the side edge hems being indicated by the numeral 4, and the 70 other by the numeral 5. These hems all lie at the inner or obverse face of the article as clearly shown in Fig. 1 of the drawings and for a purpose to be presently explained, the hem 2 is left open at its ends and, in fact, 75 is open throughout its entire length, or, in other words, of a tubular nature. The opposite hem 3 may be left open in a like manner or may be permanently closed as desired as also the side hems 4 and 5. Secured upon the inner or obverse face of the 80 hem 4 is a series of pairs of the stud members 6 of snap fastenings and secured upon the outer or reverse face of the sheet behind the side hem 5 is a series of pairs of the 85 socket members 7 of the said snap fastenings, the pairs of members 6 and 7 being correspondingly located so as to match when the right-hand edge portion *a* of the article in Fig. 1 is carried over beyond and folded 90 around behind the left-hand edge portion *b* of the article in Fig. 2. While the members 6 and 7 constitute the elements of snap fastenings, it will be understood that straps and buckles or any other suitable fastenings may 95 be employed instead thereof so long as each member thereof is wholly on one face of the material as hereinbefore specified. In like manner there is secured upon the inner or obverse face of the upper end hem 2 a series 100 of pairs of socket members 8 these members being located on portion *c* to the right of the middle of the article and along the right half of the hem as shown in Fig. 1, and secured upon the outer or reverse face of the 105 sheet behind the left half of said hem 2 is a series of pairs of stud members 9 which are designed for engagement in the socket members 8, these members 9 being located to the left of the middle of the article of Fig. 1, 110 and therefore is shown on portion *d* at the right in Fig. 2. Secured to the article at

each corner thereof, is a ring 11 of any suitable size and material, and similar rings 12 are secured to the side hems 4 and 5 substantially midway between the upper and lower ends of the article. A tape or tapes 10 are secured to the obverse of the upper hem 2 near its left end, as shown in Fig. 1. In order that a belt may be assembled with the article, a number of belt loops 13 are secured 15 to the inner face of the body portion of the article and extend in a horizontal series from one side to the other about half way between the top and bottom hems, as clearly shown in Fig. 1. Each of these belt loops 15 is preferably formed from a suitable strip of material secured at suitable intervals to the body portion of the article so that each provides a series of vertically spaced loops indicated by the numeral 14. A belt 20 15 is adapted to be threaded through the corresponding loops 14 and inasmuch as each of the members 13 provides a plurality of the loops 14, the position of the belt upon the article may be varied at will. The foregoing 25 going completes the description of the article as it is placed upon the market and there will now be described some of the more important uses to which it may be put.

In employing the article as a rain coat, 30 slicker, or the like, the sheet is held with the obverse or inner face next the wearer and thrown about the body in the manner shown in Fig. 5, the belt 15 being drawn around the waist and its ends connected in front. The lower halves of the side edges are brought together in front and the portion *a* lapped over the portion *b* and the fasteners 6 and 7 connected to each other up to about the waist line, above which line 35 the remainder of the sheet is capable of disposition about the body as shown in either Figs. 3 or 4, but in any case the reverse face of the sheet is outermost and no fasteners are exposed. If adjusted as seen in Fig. 3, the midlength of the hem 2 and the upper end of the sheet are rolled back to produce a collar effect indicated at C, whereas if adjusted as seen in Fig. 4 the hem will not be rolled back but the 40 midlength of the upper end of the sheet looped around the face to produce a hood effect designated at H. In either case the fasteners along the upper halves of the portions *a* and *b* are not to be connected, and 45 openings are thereby left for the passage of the hands; but when the upper portion of the sheet is drawn around the shoulders and body to form the cape, the outermost fasteners 8 and 9 on the portions *c* and *d* 50 are connected with each other to close the garment down the front of such cape.

In employing the article as a sleeping bag or the like, it is desirable that it be closed excepting at one end and also that 55 the disposition of parts be such as will ex-

clude rain. The sheet is now laid out flat with its outer face up as seen in Fig. 2, and first folded on a longitudinal line substantially at its transverse center so that the side edge 4 will be brought over about the 70 seam line of the hem 5, leaving portion *b* exposed. Now this portion is folded inward onto the portion *a*, and the fasteners 6 and 7 connected except perhaps those near the upper end of the sheet. The first fold 75 above mentioned brought half of the upper edge over onto the remaining half so that the portion *c* overlaid the portion *d*. The overlying portion is now slipped back a little as seen in Fig. 6, making a fold 80 along the line *e*, the hem 2 being distorted at *f* to permit; and, with the extreme upper end *g* of the portion *b* laid aside, the parts now stand as seen in Fig. 6. The next step is to fold the portion *d* (which is 85 about half the upper end) over onto the portion *c* and connect the fasteners 8 and 9. This closes most of the article being formed and brings the parts to the condition seen in Fig. 7 where the tapes are exposed, and when the distorted upper end *g* of the portion *b* is laid over into its proper place, its corner ring 11 may be engaged with the tapes and the bag is finished. Now 90 in order to prevent the entrance of rain, the entire bag is turned over so that what appears as the upper side in Figs. 6 and 7 will lie upon the earth, and therefore rain striking the other side will run off as there are no openings for it to enter.

In employing the article as a shelter tent, as shown in Fig. 9, front and rear end posts or stakes 16 are driven into the ground and the rings 12 are engaged over the upper ends of these posts or stakes, the opposite 105 side portions or, in other words, the upper and lower halves of the article in Fig. 1 being draped to extend downwardly in opposite directions as shown in the said Fig. 9. The lower edges of these portions are 110 secured by means of stakes 17 which are driven through the rings 11 and into the ground.

Having thus described the invention, what is claimed as new is:

An article of the class described including a substantially rectangular sheet of flexible material having front and rear faces, a longitudinal series of fasteners secured to the front face of said sheet along 120 one longitudinal edge portion thereof, a second series of fasteners secured to the rear face of the sheet along the opposite longitudinal edge portion thereof, said first named longitudinal edge portion being 125 adapted to overlap the second named longitudinal edge portion whereby said first and second named fasteners may be connected, a transversely extending series of fasteners secured to the front face of said sheet 130

along the lower end portion of the same and extending only half way across said sheet; and a second series of transversely extending fasteners secured to the rear face of said sheet at the same end portion of the sheet and extending across the other half of the sheet only, the first named half of

the lower end portion of said sheet being adapted to be folded upon said second half of the same whereby the first and second 10 named series of transversely extending fasteners may be connected.

In testimony whereof I affix my signature.
E McIVOR LAW. [L. s.]
